UNITED STATES PATENT OFFICE.

EDWIN E. MILNER, OF SCOTT TOWNSHIP, AND WILLIAM J. LYTTLE, OF ROSSLYN FARMS BOROUGH, ALLEGHENY COUNTY, PENNSYLVANIA, ASSIGNORS TO H. L. DIXON COMPANY, OF CARNEGIE, PENNSYLVANIA, A CORPORATION OF PENNSYLVANIA.

MUFFLE-FLATTENING OVEN AND LEER.

1,426,309.

Specification of Letters Patent. Patented Aug. 15, 1922.

Application filed August 12, 1921. Serial No. 491,701.

To all whom it may concern:

Be it known that we, EDWIN E. MILNER, residing at Scott Township, and WILLIAM J. LYTTLE, residing at Rosslyn Farms Borough, Allegheny County, Pennsylvania, have invented a new and useful Improvement in Muffle-Flattening Ovens and Leers, of which the following is a full, clear, and exact description.

0 Our invention relates to muffle flattening ovens and leers, and particularly to muffle flattening ovens and leers for treating glass.

An object of our invention is such a device wherein the flues are muffled for heating the glass roller.

A further object of our invention is such a device wherein the flattening oven has the highest temperature of any part of the device.

0 A further object of our invention is such a device wherein the piling station has the lowest temperature, means being provided for increasing the temperature of the piling station as described.

5 A further object of our invention is such a device wherein each flue is provided with an independent regulator.

A further object of our invention is such a device wherein a uniform temperature is secured and which temperature is under the control of the operator.

Furthermore the device is economical in operation and the arrangement is such that by reason of the individual regulation of the flues a higher temperature may be maintained at the doors so as to offset the natural tendency of that part of the device to be cooler than the remaining parts.

Further objects will be apparent to those skilled in the art and our invention will be better understood by reading the following description taken in connection with the accompanying drawings, in which:

Figure 1 is a sectional plan view embodying our invention;

Figure 2 is a section on line II—II of Figure 1; and

Figure 3 is a section on line III—III of Figure 1.

0 The device comprises a foundation 1 upon which the device is carried. Placed upon the foundation 1 are side walls 2. Mounted upon the central foundation member 1 is a shaft 3 which carries supporting members 4 upon which is placed a refractory

member 5, and upon which the articles are flattened. Rods 6 connect the outer ends of the members 4 to the shaft 3. The shaft 3 is provided with a bevel gear 7 which meshes with a gear 7^a mounted on the shaft 60 8 and journaled at 8^a and operated through a sprocket 9 from any suitable source of power for rotating the shaft 3 and the member 5. The area over the turn table is divided into four compartments A, B, C and 65 D. The compartment A is the flattening oven; B is the piling station; C is the first rod station and D is a "dummy" oven. This space is divided by the overhanging partitions 10 supported by any suitable means. 70 For the purpose of heating the chambers A, B and C the top wall of the device is provided with a plurality of flues 11. These flues are composed of tile members held in place by I-shaped key blocks 11^a, supported 75 from channels 12 carried by the framework of the device. Each of the flues is provided with a burner 13, supplied from a gas flue 14, and provided with air through the conduit 15. Each of the flues 11 has a separate 80 combustion chamber 16 and also two off-takes 17 and 18. The off-takes 17 and 18 are provided with dampers 19 and 20 controlled by any suitable means. The off-takes 85 17 on the different flues communicate with a header 21 and likewise the off-takes 18 communicate with a header 22, and the headers 21 and 22 communicate with a stack 23.

As shown in Figure 3, a shade stone 24 90 is provided along the region of the device where the combustion chambers 16 communicate with the flues. The object of this shade stone is to protect the glass roller 25, shown in dotted lines in Figure 3, from too 95 high a temperature immediately upon being placed in the device. Furthermore, the highest temperature in the flue is in the region of the juncture of the combustion chamber 16 with the flues and the rollers are 100 therefore protected against this high temperature by the shade stone.

Figure 1 shows the arrangement wherein the roller is introduced into the flattening oven by the tool 26, by which the roller is 105 pushed into the flattening oven in any suitable manner.

The operation of the device is as follows:

The roller or shawl is introduced by the tool 26. The article is flattened on the 110

stone 5 in the flattening oven A and is then conducted to the piling station B by revolving the stone 5. At this point, the flat sheet is lifted off the stone by means of a usual piling fork and placed on the rods in the first rod station C, and is then carried by the rods 27 through the annealing leir 28, part of which is shown in Figure 1.

Each of the flues 7 has independent means 10 for controlling the temperature thereof, the means comprising the dampers 19 and 20. If it is desired to vary the temperature of the compartment of the piling station, this may be done by properly manipulating the 15 dampers 19 and 20. If, for instance, the temperature of that compartment is lower than required, the damper 19 may be closed and the damper 20 opened so that the gases will pass through the entire length of the flues 20 10 and raise the temperature of that compartment substantially to that of the flattening oven compartment. If it is desired to decrease the temperature of the compartment B, the damper 20 may be closed partially or 25 altogether, and the damper 19 opened so that the heating gases will pass through only a portion of the flue 11, thus allowing the temperature of the compartment B to decrease. These temperatures may be further controlled by controlling the supply of fuel to 30 the flues.

From the foregoing, it will be apparent that our invention has many advantages, among which may be mentioned that the 35 temperature may be uniformly regulated and varied in the different compartments; by reason of the muffle construction and the individual temperature control, great economy is effected in fuel consumption, as the drafts 40 incident to a direct heating arrangement are avoided; by reason of the individual temperature control, the flues near the doors where the articles are introduced and removed may be at a higher temperature than 45 the other flues, thus tending to create a tendency for the hot gases to flow out of the device instead of permitting the cold air to rush thereinto; the advantages of the shade stone are secured thus eliminating breakage 50 due to high temperatures or too rapid rise of temperature upon introducing the article into the device.

Further advantages will be apparent to those skilled in the art.

55 While we have shown and described the preferred form of our device in detail, it will be understood that we are not limited to the exact arrangement and construction shown and described, as many changes may be made 60 in the details without departing from the spirit of our invention.

We claim:

1. A flattening oven comprising a flattening stone, a chamber above said stone and 65 means for indirectly heating said chamber.

2. A flattening oven comprising a flattening stone, a plurality of chambers above said stone, and means for indirectly heating said chambers to different temperatures.

3. A flattening oven comprising a flattening stone, a chamber above said stone, means subdividing said chamber into a plurality of parts and means for indirectly heating said parts to different temperatures. 70

4. A flattening oven comprising a rotatable flattening stone, a chamber above said stone and means for heating said chamber indirectly and means for rotating said stone. 75

5. A flattening oven comprising a flattening stone, a chamber above said stone, means 80 dividing said chamber into a plurality of parts, means for indirectly heating said parts to different temperatures and means for rotating said stone to place a given point therein in any one of the parts of said chamber. 85

6. A flattening oven comprising a flattening stone, a chamber above said stone, and a plurality of flues in the top wall of said chamber for heating the chamber. 90

7. A flattening oven comprising a flattening stone, a chamber above said stone, means dividing said chamber into a plurality of parts, flues in the top wall of said chamber for heating said parts to a different temperature, and means for controlling the passage of heating gases through said flues to vary the temperature in said parts. 95

8. A flattening oven comprising a flattening stone, a chamber above said stone, heating flues in the top wall of said chamber and an individual combustion chamber for each of said flues. 100

9. A flattening oven comprising a flattening stone, a chamber above said stone, a 105 plurality of flues in the top wall of said chamber, a combustion chamber for each of said flues, and a shade stone near the juncture of each combustion chamber with its flue. 110

10. A flattening oven comprising a flattening stone, a chamber above said stone, a plurality of flues in the top wall of said chamber, a combustion chamber for each of said flues, a shade stone near the juncture of each 115 combustion chamber with its flue, and means producing combustion in said combustion chamber.

11. A flattening oven comprising a flattening stone, a chamber above said stone, means 120 dividing said chamber into a plurality of parts, flues in the top wall of said chamber extending across a plurality of said parts, and means for directing the heating gases in said flues over one or more than one of said parts. 125

12. A flattening oven comprising a flattening stone, a chamber above said stone, means dividing said chamber into a plurality of parts, a plurality of flues in the top 130

wall of said chamber, and a plurality of off-takes for each of said flues.

13. A flattening oven comprising a flattening stone, a chamber above said stone, means dividing said chamber into a plurality of parts, a plurality of flues in the top wall of said chamber, a plurality of off-takes for each of said flues, and means for controlling the flow of gases through one of said off-takes.

14. A flattening oven comprising a flattening stone, a chamber above said stone, means dividing said chamber into a plurality of parts, a plurality of flues in the top wall of said chamber, a plurality of off-takes for each of said flues, and means in each of said off-takes for controlling the passage of gas therethrough.

15. A flattening oven comprising a flattening stone, a chamber above said stone, a plurality of flues in the top wall of said chamber, and means for independently regulating the temperature of each of said flues.

16. A flattening oven comprising a flat-

tening stone, a chamber above said stone, means dividing said chamber into a plurality of parts and a plurality of flues in the top wall of said chamber, and means regulating the passage of heating gases through said flues to regulate the temperature of each of the parts of said chamber.

17. A flattening oven comprising a flattening stone, a chamber above said stone, a plurality of flues in the top wall of said chamber, an off-take at one end of each of said flues and an off-take for each of said flues intermediate its ends.

18. A flattening oven comprising a flattening stone, a chamber above said stone, a plurality of flues in the top wall of said chamber, an off-take at one end of each of said flues and an off-take for each of said flues intermediate its ends, and means for regulating the flow of gases in said off-takes.

In testimony whereof, we have hereunto set our hands.

EDWIN E. MILNER.
WILLIAM J. LYTLE.
